UNITED STATES PATENT OFFICE.

CHARLES R. WOOD, OF FARGO, NORTH DAKOTA.

OVERALLS.

Application filed September 13, 1922. Serial No. 588,015.

To all whom it may concern:

Be it known that I, CHARLES R. WOOD, a citizen of the United States, residing at Fargo, in the county of Cass and State of North Dakota, have invented certain new and useful Improvements in Overalls, of which the following is a specification, reference being had to the accompanying drawings.

10 This invention relates to improvements in overalls, and more particularly to an improvement in the construction and arrangement of the pockets thereof.

15 A particular object of the invention is to provide a novel and improved compound pocket for the reception of a rule, pliers and pencils, and so to arrange the pocket that the multiple arrangement will occupy as small a space as is feasible.

20 A further object of the invention is to provide in overalls a pocket construction whereby the hip pocket ordinarily applied to the overalls is so located with relation to the rule and plier pocket that it reinforces that 25 portion of the same ordinarily subjected to the greatest strain.

25 A still further object of the invention is to provide a construction of this character wherein the plier pocket is reinforced at all 30 points where the pliers normally subject the pocket to the greatest strain and accordingly at the points where the pockets normally wear out destroying the use of the overalls and necessitating the purchase of a new pair.

35 These and other objects I attain by the construction and arrangement shown in the accompanying drawings wherein for the purpose of illustration is shown a preferred embodiment of my invention and wherein like reference characters designate like parts throughout.

In the drawings:—

40 Figure 1 is a fragmentary side elevation of a garment showing pockets constructed in accordance with my invention applied thereto.

Figure 2 is a rear elevation thereof, parts being broken away;

Figure 3 is a section on the line 3—3 of 45 Figure 1;

Figure 4 is a section on the line 4—4 of Figure 1;

Figure 5 is a section on the line 5—5 of Figure 1; and

50 Figure 6 is a section on the line 6—6 of Figure 1.

Figure 7 is a detail sectional view on the line 7—7 of Figure 2.

Referring now more particularly to the drawings, the numeral 10 indicates a back leg section of a pair of overalls and 11 a front leg section connected by the usual seam 12. In accordance with my invention, I apply to the outer surface of the rear leg section a piece of material 13, one longitudinal edge of which is included in the seam 12 and the opposite edge of which is stitched to the rear leg section, as indicated at 14. From its upper edge to a point approximately midway its length adjacent the stitching 14 but spaced therefrom, this material is split vertically, dividing the upper end of the piece 13 into sections 13^a and 13^b. To the free edge of the section 13^a, or that section having one edge thereof included in the seam 12, I secure a strip of material 15 which is extended over and overlaps the section 13^b at its edge and is then folded back upon the face of the section 13^a and has its free edge included in the seam 12 between the front and back leg sections. The free edge of the section 13^b is reverted and has stitched thereto upon its inner face a reinforcing strip 16, the free edge of which is included in the stitching 14 by means of which the material 13 of the piece 13 is secured to the leg section 10. 55

By the above construction, the upper section of the pocket formed by the application of the piece 13 to the rear leg section is provided at its upper end with reinforcing sections doubling the thickness of such upper end and providing a hand opening to the pocket, the edge of the hand opening having overlapping flaps. The upper edge of the section 13^b is stitched to the leg section 10, as indicated at 17, the stitching likewise extending through the reinforcing strip 16. Stitching is further applied to the section 13^a along the upper edge thereof and to that portion of the strip 15 which overlaps the section 13^b, the stitching at the last named point extending through not only the strip 15 but through the section 13^b, reinforcing strip 16 and the material of the leg section 10. By this stitching the upper end of the plier pocket is closed and it will be noted that the overlap of the pocket flaps is doubly secured in position. 100

To further reinforce the pocket flap and the upper end of the plier pocket in the application of the usual hip pocket 18, the same is so positioned that the lower corner thereof 105

overlaps the upper edge of the section 13^b so that the stitching 19, by means of which the pocket 18 is secured to the section 10, will extend through these pocket flaps and 5 through the section 13^b, reinforcing strip 16, and the material of the leg section 10. Four rows of stitching are thus applied to 10 secure the upper edge of the pocket flaps and the upper corner of the plier pocket in position; stoutly reinforcing these points which, as well known to those familiar with the art, are the points at which the drag of inserting and removing the hand from the pocket is applied and at which points breakage of the 15 threads securing the pocket in position most often occurs. It will be noted that this doubling of the stitches is accomplished without the necessity of applying further stitches than those ordinarily necessary to secure the 20 various sections of the two pockets in position and without applying more than the double row of stitching ordinarily applied in securing any single part. It will further be noted that by the construction recited, 25 the section 13^a and strip 15 combine to form a pocket which is open at its upper end, as indicated at 20, for the reception of a rule or the like.

The lower end of the plier pocket is reinforced by a section of material 21 having its 30 side edges included in the seam 12 and the stitching 14 and its lower edge stitched together with the lower edge of the piece 13 to the section 10. The upper edge of the section of material 21 has its upper edge extending slightly above the upper edge of the split of the piece 13 and secured thereto at the point of overlap of the pocket flaps, the stitching 21^a extending through the section 21 and through both of the flaps securely connecting together the lower ends of the flaps and this section. This stitching divides the 40 upper end of the reinforcing section 21 into two parts, each of which has an opening at its upper end so that a pencil or the like may be inserted between the rear face of the piece 13 and the section 21 at these points and being held within the pocket and at a point 45 where it is not likely to be lost and at the same time is readily accessible.

From the foregoing it is believed to be 50 obvious that a pocket construction in accordance with my invention is particularly well adapted for use in the construction of mechanic's overalls in that the pocket is provided for the reception of pliers and the like, which is doubly reinforced throughout 55 its length preventing the angular portions and corners of the pliers from wearing 60 through the material of the pocket while the overalls are still serviceable. It will likewise be obvious that by the construction hereinbefore employed, this reinforcement is put to a maximum use and the presence of 65 dead material employed only for reinforce-

ing and serving no other function is reduced to a minimum. It will furthermore be obvious that the construction as hereinbefore set forth is capable of some change and modification without materially departing 70 from the spirit of my invention and I accordingly do not limit myself to such specific structure except as hereinafter claimed.

I claim:

1. The combination with a garment of the 75 class described, of a piece of material secured at its edges to the garment and combining therewith to form a pocket, said piece having a vertical slit opening through the upper edge thereof and affording access to the 80 pocket, strips of material secured to said piece at the edges of said slit and having their free edges folded back upon the material at opposite sides of the slit and secured to the material at its edges, one of said 85 strips being disposed upon the outer face of the piece of material and having its bottom edge secured to the piece whereby to form a pocket open at its upper end, one of said pieces extending over said slit to thereby 90 form a pocket flap.

2. The combination with a garment of the 95 class described, of a piece of material secured at its upper edges to the garment and combining therewith to form a pocket, said piece having a vertical slit affording access to the pocket, a strip of material secured at one edge to the piece at one side of the slit and at its opposite edge to the side edge of the piece at the same side of the slit, said 100 material extending over and covering said slit and having its bottom edge secured to the piece, whereby said strip forms a flap covering the pocket opening of said pocket and combines with the piece of material to 105 form a pocket open at its upper end, and a reinforcing section disposed within the pocket and having its side and bottom edges included in the stitching securing the piece 110 of material to the garment, the upper edge of said reinforcing section extending slightly above the lower end of said slit and being secured to the piece and strip whereby to reinforce the material at the lower end of 115 said slit.

3. The combination with a garment of the 120 class described, of a piece of material secured at its upper edges to the garment and combining therewith to form a pocket, said piece having a vertical slit affording access 125 to the pocket, a strip of material secured at one edge to the piece at one side of the slit and at its opposite edge to the side edge of the piece at the same side of the slit, said material extending over and covering said slit and having its bottom edge secured to the piece whereby said strip forms a flap covering the pocket opening of said pocket and combines with the piece of material to 130 form a pocket open at its upper end, and a

- reinforcing section disposed within the pocket and having its side and bottom edges included in the stitching securing the piece of material to the garment, the upper edge 5 of said reinforcing section extending slightly above the lower end of said slit and being secured to the piece and strip whereby to reinforce the material at the lower end of said slit, the upper edge of said reinforcing section 10 at the sides of the slit being free from connection with said piece whereby to form between said reinforcing section and piece pockets adapted for the reception of pencils and the like.
- 15 4. The combination with a garment of the class described, of a piece of material secured at its edges to the garment and combining therewith to form a pocket, said piece having a vertical slit opening through the upper 20 edge thereof and affording access to the pocket, strips of material secured to said piece at the edges of said slit and having
- their free edges folded back upon the material at opposite sides of the slit and secured to the material at its edges, one of said strips being disposed upon the outer 25 face of the piece of material and having its bottom edge secured to the piece whereby to form a pocket open at its upper end, one of said pieces extending over said slit to thereby form a pocket flap, and a reinforcing 30 section disposed within the pocket and having its side and bottom edges included in the stitching securing the piece of material to the garment, the upper edge of said reinforcing section extending slightly above 35 the lower end of said slit and being secured to the piece and strip whereby to reinforce the material at the lower end of said slit.

In testimony whereof I hereunto affix my 40
signature.

CHARLES R. WOOD.
